United States Patent

Des. 239,722

Patented Apr. 27, 1976

239,722

MICROPHONE

Arthur W. Schmidt, Chicago, Ill., assignor to
Shure Brothers Incorporated

Filed May 23, 1974, Ser. No. 472,628

Term of patent 14 years

Int. Cl. D14—01

U.S. Cl. D26—14 J

FIG. 1

FIG. 2

FIG. 3

FIG. 4

FIG. 1 is a perspective view of a microphone showing my new design;

FIG. 2 is a top plan view thereof;

FIG. 3 is one side view thereof, the other side view being substantially identical; and

FIG. 4 is a bottom plan view thereof.

I claim:

The ornamental design for a microphone, as shown and described.
